United States Patent Office.

WILLIAM AIKIN AND WILLIAM BENNETT, OF LOUISVILLE, KENTUCKY, (SAID BENNETT AS ADMINISTRATOR OF THE ESTATE OF J. R. GATES, DECEASED,) ASSIGNORS TO J. F. PEARSON AND WILLIAM AIKIN, OF SAME PLACE.

Letters Patent No. 85,984, dated January 19, 1869.

IMPROVEMENT IN SUGAR-CANE MILLS.

The Schedule referred to in these Letters Patent and making part of the same.

To all whom it may concern:

Be it known that WILLIAM AIKIN, and J. R. GATES, now deceased, of Louisville, in the county of Jefferson, and State of Kentucky, did invent a new and improved Sugar-Cane Press; and we, the said WILLIAM AIKIN, and WILLIAM BENNETT, administrator of the estate of the said J. R. GATES, deceased, do hereby declare that the following is a full, clear, and exact description thereof, which will enable others skilled in the art to make and use the same, reference being had to the accompanying drawings, forming part of this specification, in which—

Figure 1 represents a side elevation, partly in section, of this improved sugar-mill.

Figure 2 is a horizontal section of the same, taken on the plane of the line x x , fig. 1, the view being inverted.

Figure 3 is a plan or top view of the same.

Figure 4 is a detail top view of one of the rollers, showing the kind of clutch used to drive it.

Figure 5 is a detail horizontal section of one of the journal-boxes, the plane of section being indicated by the line y y , fig. 1.

Similar letters of reference indicate corresponding parts.

This invention relates to certain improvements in sugar-cane mills, and has for its object to simplify the construction of the whole apparatus, and especially to provide adjustable and good bearings for the rollers, and facilities for lubricating and repairing the same.

The invention consists in the application of removable journals, which are also made adjustable horizontally, by means of screws, to increase or relieve the pressure.

The invention consists, also, in the application of a yielding scraper, for cleaning the roller, and in a new means for retaining the grease in the lower journals.

A, in the drawing, represents the shell of this improved sugar-mill.

B is the upper, and

C, its lower head.

D E F are the three rollers for compressing the cane, and extracting the juice therefrom.

The axle a of the large roller D fits into blocks, that are fitted into apertures formed through the two heads B C. The blocks are perforated to receive the axles.

The axles b b of the rollers E F are fitted into similar blocks, c c , that fit into apertures formed through the heads B C.

The blocks in the top plate B are perforated, to allow lubricating-matter to be put in from above, while those in the bottom plate have only sockets for the axles, so that they will retain the oil.

The receptacles for these blocks are enlarged by flanges d d , projecting from the heads, as shown in figs. 1, 3, and 4.

The blocks are somewhat smaller than the boxes in which they are held, and are, by means of set-screws, e e , regulated, so that they may carry the rollers more or less together, to obtain the desired effect upon the cane.

From the lower head, C, project circular flanges ff around the apertures, for the axles, to retain the grease.

The rollers rest with their lower ends on these flanges, to cover up the vessels formed by them, and to prevent the juice of the cane from coming in contact with the oil or lubricating-matter.

The apertures in the blocks c may be elongated, as shown in fig. 5, so that the rollers may have slight play in them.

The blocks c are covered by slides g g , which are dovetailed into the upper flanges d , as shown in figs. 3 and 1.

By removing the cover g , the block c , protected by it, can be removed, repaired, or the journals can be lubricated.

The large roller, D, receives direct rotary motion by means of a crank or lever, G, on its axle a .

On its upper end are formed lugs, that mesh into a toothed wheel, h , which fits loose around the axle a .

This wheel gears into pinions i i , that fit loose around the axles b of the rollers E F, and imparts motion to them.

The wheels i have lugs j formed on their under sides, that catch against lugs k , projecting from the rollers, as indicated in figs. 1 and 4, and the said rollers are thus revolved as long as the wheels rest on the rollers, but when, by the accumulation of matter within, the case should become filled, the wheels will, by said matter, be raised off the rollers, and will thereby throw the same out of gear.

H is a scraper, pivoted in the heads B C. Its axle or pivot-pin projects through the upper head, and has an arm, l , between the end of which and a flange, d , a rubber spring, m , is interposed, so that thereby the said scraper is made yielding and elastic.

The edge of the scraper rests against the periphery of one of the rollers, and there may be as many scrapers used as there are rollers.

We claim as new, and desire to secure by Letters Patent—

1. The combination of the perforated blocks c , the flanges d , sliding covers g , and set-screws e , substantially as described, for the purpose specified.

2. The lower head C, constructed as described, cast with the outer grooved flanges d , for the reception of the blocks c and sliding covers g , and with the inner circular flanges ff supporting the rollers, as herein set forth and shown.

3. Driving the rollers E F by means of pinions i i , that fit loose around their axles, and are connected by clutches with the rollers, substantially as described, for the purpose of preventing the accumulation of matter in the mill, as set forth.

WILLIAM AIKIN.
WM. BENNETT,
Administrator of J. R. Gates.
